UNITED STATES PATENT OFFICE.

ARTHUR FALK, OF NEW YORK, N. Y., ASSIGNEE TO FALK TOBACCO COMPANY, OF NEW YORK, N. Y.

DISPENSING-PACKAGE.

1,117,016.

Specification of Letters Patent.

Patented Nov. 10, 1914.

Application filed May 27, 1914. Serial No. 341,286.

To all whom it may concern:

Be it known that I, ARTHUR FALK, a citizen of the United States, residing at New York, in the county of New York and State 5 of New York, have invented certain new and useful Improvements in Dispensing-Packages, of which the following is a specification.

This invention relates to the subject of 10 packages for cigarettes, and the primary aim of the invention is to produce a cigarette package which will prevent the contents of the package from deterioration and permit access to be freely had to said contents.

The invention contemplates a cigarette package the inner wrapper of which is formed of air and moisture proof material having its ends folded and overlapped to 20 seal the ends of the package, one of the ends being so formed that it may be readily opened to permit a cigarette to be removed and said end then restored to its normal position to seal the package, the package 25 being inclosed in a wrapper one end portion of which is weakened and folded to form sealing flaps which, when opened, form a finger grip that facilitates tearing-off the weakened portion of the outer wrapper, so 30 that access may be had to the end of the package that is to be opened to give access to the cigarettes, the removable end of the wrapper being so disposed relative to the package that when said end is removed, the 35 wrapper remains on and forms a protector that prevents the package collapsing.

One simple and preferred embodiment of the invention is shown in the accompanying drawings, wherein—

40 Figure 1 is a perspective view of the improved package, the outer wrapper having its removable end in position to be torn-off to give access to the loose flaps of the inner wrapper. Fig. 2 is a perspective view showing the removable end partly detached and exposing the loose flaps of the inner wrapper. Fig. 3 is a perspective view, the removable end of the outer wrapper being torn-off and the adjacent end of the inner 45 wrapper being opened. Fig. 4 is a plan view of the outer wrapper.

The improved package comprises an inner wrapper 1 formed of tin foil or other air and moisture proof material, and a loose paper lining 2 therefor. The wrapper 1 and

the lining 2 are shaped to form a container which may be rectangular or any other shape, and the ends thereof are folded to form the side flaps 3 and top and bottom flaps 4 and 5 respectively. The bottom flaps 60 5 are folded inwardly, the side flaps 3 then folded onto the flaps 5, and the top flaps 4 are then folded over the said side and bottom flaps. The flaps are tightly folded in their overlapped relation described, and at 65 one end, adhesive material is used to permanently retain the flaps sealed in such overlapped relation. At the other end of the container, the flaps are not permanently connected as the same are to be opened to 70 permit access to be had to the container for removal of the contents thereof, as will be explained. The last-mentioned flaps, that is, the ones that are not permanently sealed, are hereinafter referred to as "loose flaps." 75

The relative disposition of the inner wrapper 1 and the lining 2 is such that their longitudinal edges overlap by a considerable margin, a feature of the invention that is of importance in that in such arrangement 80 seals the meeting edges of said wrapper and lining, and also forms a reinforcement at such point of four layers of the wrapper and lining, as indicated generally by the numeral 6. The overlapped portions of the 85 wrapper 1 and lining 2 are preferably not permanently connected, but obviously adhesive material may be used to obtain a permanent connection if such is desired.

The package so far described is an air 90 and moisture proof one, the end thereof that is closed by the loose flaps being sealed tight by said flaps as the foil wrapper 1 retains the shape and position in which it is folded, yet such loose flaps can be readily 95 opened to permit the removal of a cigarette, and then readily restored to their overlapped positions to tightly seal the package, such opening and closing of the loose flaps having no tendency to damage the package. 100

An outer wrapper 7 incloses the package, the wrapper 7 being preferably of paper and in the form of an advertising label. The ends of the wrapper 7 are folded to form side flaps 8, bottom flaps 9 and top 105 flaps 10, similar to the flaps of the wrapper 1 and lining 2. The flaps of the wrapper 7 at the permanently sealed end of the wrapper 1 are also permanently sealed in overlapped relation, and at the other end of 110

wrapper 7, the flaps are folded in overlapped relation in a manner similar to the folding of the loose flaps, and the top flap 10 is supplied with a small amount of adhesive material, just sufficient to cause it to lightly adhere to the bottom flap 9. At the junction of the body of the wrapper 7 and its sealing flaps 8, 9 and 10, the body is weakened transversely by the indentations, 10 perforations, or other weakening means, 11, so that by releasing the flap 10 from the flap 9 and using said flap 10 as a finger grip, the entire end portion of the wrapper 7 may be readily torn-off at the weakened 15 portion 11 so that the loose flaps of the wrapper 1 and lining 2 are exposed and may be opened to give access to the contents of the package.

It will be observed that the flaps 8, 9 and 20 10 are provided by infolding the sides to form the flaps 8, and such infolding causes the top flap 10 to be formed of two layers of material, an advantageous feature in that sufficient reinforcement is thereby imparted 25 to the flap 10 so that when said flap is used as a finger-grip, it assures that the strain exerted will cause the end of the wrapper to be separated from the body thereof at the weakened line 11.

30 The label 7 entirely incloses the package and its longitudinal meeting edges are permanently connected by the use of adhesive material. This arrangement, combined with the permanently sealed end of the wrapper, 35 or label, causes the label to form a cup-shaped protector in which the package remains after the weakened end of the label has been removed, that retains the package in its original shape and also prevents the 40 contents of the package being damaged by displacement or otherwise.

The improved package is of special utility

in connection with cigarettes and tobacco generally in that the same normally preserves the contents from the deteriorating 45 effects of air and moisture, yet provides simple means whereby access can be had to the contents when desired, and afterward the package can be readily sealed against air and moisture without damaging the package. 50 And in this connection it is to be noted that the use of the package is not limited to cigarettes, tobacco, and other tobacco articles, for it will be clear that the same may be used as a container for a large 55 variety of articles.

What I claim as my invention is:—

A merchandise package comprising an inner wrapper formed of air and moisture proof material shaped to form a container 60 having one end permanently sealed, the other end of the container being folded to form flaps that are loosely overlapped to permit the same to be opened to give access to the contents of the container, and a label 65 inclosing the container and having one end permanently sealed and its other end folded to form overlapping flaps that are independent of the flaps of the container and adapted to be opened, the label being shaped 70 to form a cup-shaped receptacle that holds and protects the container, said label at the junction of its major portion and its overlapping flaps being circumferentially weakened to permit said overlapping flaps to be 75 torn from the said major portion to give access to the loose flaps of the container.

In testimony whereof I have affixed my signature in presence of two witnesses.

ARTHUR FALK.
